GLOBE MOUNTING

Raymond R. Dupler, Toledo, Ohio

Application July 10, 1935, Serial No. 30,609

4 Claims. (Cl. 240—128)

This invention relates to mountings for globes, or similar spherical objects, and an object is to produce a simple and efficient mounting of this character which can be inexpensively manufactured and installed, affords a satisfactory and substantial support for the globe, and has the new and improved features of construction hereinafter described.

An embodiment of the invention is shown on the accompanying drawing, in which:

Figure 1 is a side elevation partly in section showing a globe and the mounting therefor;

Figure 2 is an enlarged fragmentary sectional view showing the tube prior to attachment to the globe;

Figure 3 is an enlarged fragmentary elevation of the tubular supporting post; and

Figure 4 is a fragmentary sectional elevation of an alternate form of mounting.

The illustrated embodiment of the invention comprises a tubular supporting element 10, which may form a part of a figure, such as the upper end of an arm or a pedestal of any suitable shape and configuration. The upper end of the support 10 terminates in a cylindrical portion 11, and suitably fixed thereto is a spool-like member having upper and lower cylindrical surfaces 13 and 14 respectively, and an intermediate smaller portion. Below the cylindrical portion 14 is an outwardly projecting annular flange 15 providing a supporting ledge 16. The cylindrical surface 14 is slightly larger than the surface 13 for the purpose hereinafter described.

The support 10 and spool 12 are hollow, and extending therethrough is a tube 17, on the upper end of which is mounted a socket 18 for an elongate lamp bulb 19, it being understood that suitable wires (not shown) extend through the tube 17 and lead to the lamp socket 18.

There is provided a globe or sphere 20 of glass or other suitable translucent material. The globe 20 is imperforate except for an opening 21 at the lower end thereof, and fitting in the opening 21 is a sleeve 22 of metal, or other suitable material, which is slightly longer than the spool 12. Formed adjacent the lower end of the sleeve 22 is an outwardly projecting inwardly tapered flange or rim 23. The globe 20 is covered by a plurality of segments or sections 24 of sheet material, such as paper, and in this instance depicted on these sections, which mate with one another, is a map of the world. The lower ends of the sections 24 terminate adjacent the opening 21, and these ends are covered and secured in place by the flange or rim 23, which is ce-

mented in place to the globe and sections 24. This not only provides a neat appearance, but is effective in covering the lower edges of the sections as well as insuring that they will be retained in place. It will be noted that the sleeve 22 projects a substantial distance inside of the globe, and formed on the inside of the sleeve 22 above the rim 23 is an annular shoulder 25, which is adapted to seat on the annular flange or ledge 16. The cylindrical portion 14 of the spool 12 fits closely within the sleeve 22, although more clearance is provided between the cylindrical portion 13 of the spool. The cylindrical portion 13 prevents the globe from being cramped and adds to its stability, but the globe is free to turn about the ledge 16. It will be noted that the sleeve 22 engages the peripheral surface of the flange 15, and the lower portion of the sleeve substantially covers the cylindrical portion 11 of the supporting tube to provide a finished appearance. It will also be apparent that a portion of a sleeve 22 projects below the rim 33.

The form of the invention shown in Figure 4 is similar to that above described except that the socket 18a is provided with a snap-on-and-off switch, from which leads a chain 26 passing through openings 27 and 28 in the portions 13a and 14a of the spool. The lower end of the chain is disposed below the globe in position to be grasped to switch the light on and off in the usual manner.

From the above description it will be apparent that I have provided a simple but satisfactory mounting for the globe, which enables it to be properly mounted with the lamp inside of it but free to turn relative to the lamp so that where the map of the world is displayed it can be conveniently turned in order readily to observe different portions thereof. The globe can be conveniently mounted in position of use or removed easily at any time for purpose of shipment or to replace the lamp bulb.

It is to be understood that changes in details of construction and arrangement may be effected without departing from the spirit of the invention, especially as defined in the appended claims.

What I claim as new and desire to secure by Letters Patent is:

1. A device of the class described comprising a vertically disposed tubular member, a pair of vertically spaced cylindrical surfaces in juxtaposed relation to and in axial alignment with said member, an annular flange below the lower cylindrical surface, a translucent globe-like member having an opening, a sleeve extending

- entirely inside of said globe-like member through said opening except for an outwardly extending flange engaging the outside of said globe-like member, a shoulder on the inside of said sleeve spaced from the outer end thereof and adapted to rest against and be supported rotatably by said annular flange, and an elongate lamp carried by said tubular support and adapted to extend inside of said globe-like member for illuminating the same.
2. A device of the class described comprising a vertically disposed tubular member, a pair of vertically spaced cylindrical surfaces in juxtaposed relation to and in axial alignment with said member, an annular flange below the lower cylindrical surface, a translucent globe-like member having an opening, a sleeve extending inside of said globe-like member through said opening and having an outwardly extending flange engaging the outside of said member, and sheet material on the outer surface of said globe-like member and having the lower edges thereof covered and held in place by said outwardly extending flange.
3. A device of the class described comprising a vertically disposed tubular supporting member, a pair of vertically spaced cylindrical surfaces adjacent to and in axial alignment with said member, said surfaces having openings arranged in alignment, an annular flange below

the lower cylindrical surface, a translucent globe-like member having an opening, a sleeve extending inside of said globe-like member through said opening and having an outwardly extending flange engaging the outside of said member, a shoulder on the inside of said sleeve adapted to rest against and be supported by said annular flange, an elongate lamp carried by said tubular support and adapted to extend inside of said globe-like member for illuminating the same, a switch for said lamp, and a flexible cable leading from said switch and passing through the openings in said cylindrical surfaces with the outer end thereof in position to be grasped.

4. A device of the class described comprising a vertically disposed tubular member, an outwardly projecting cylindrical guide in axial alignment with said tubular member, a supporting flange at one end portion of said guide a translucent globe-like member having an opening, an elongate sleeve within said opening, fitting over said cylindrical guide, and in supporting relation to said flange, and a flange on the lower end of said sleeve and engaging the outer side of said globe-like member, said sleeve being disposed entirely within said globe-like member except for said last flange and being rotatable about said guide.

RAYMOND R. DUPLER. 30
